UNITED STATES PATENT OFFICE

118,568

DESIGN FOR A COMBINED CIGARETTE DISPENSER AND CLOCK

Harry Rubin, New York, N. Y.

Application June 27, 1939, Serial No. 85,717

Term of patent 3½ years

To all whom it may concern:

Be it known that I, Harry Rubin, a citizen of the United States of America, residing at New York, in the county of New York and State of New York, have invented a new, original, and ornamental Design for a Combined Cigarette Dispenser and Clock, of which the following is a specification, reference being had to the accompanying drawing, forming part thereof, and in which:

Figure 1 is an elevational view of a combined cigarette dispenser and clock embodying my new design, and

Figure 2 is a top plan view thereof.

I claim:

The ornamental design for a combined cigarette dispenser and clock, substantially as shown.

HARRY RUBIN.
